CLAIM

The ornamental design for a brassiere, as shown and
described.

DESCRIPTION

FIG. 1 is a perspective view of brassiere showing my
new design;

FIG. 2 is a front elevational view thereof spread flat;
and

FIG. 3 is a rear elevational view of FIG. 2.
The broken lines shown in the figures represent conventional
stitching.

Fig. 1.

FIG. 2.

FIG. 3.
